BUS TRANSFER APPARATUS

Kurt Mahnke, Alden, N. Y., assignor to Westinghouse Electric Corporation, East Pittsburgh, Pa., a corporation of Pennsylvania

Application April 8, 1948, Serial No. 19,846

9 Claims. (Cl. 171—97)

1

My invention relates to bus transfer apparatus for selectively energizing a load from any one of several power sources.

It is an object of my invention to provide bus transfer apparatus capable of automatically connecting a load circuit to one of three or more supply sources in a predetermined order of preference. Another object of the invention is to devise such apparatus as a compact and largely self-contained unit in which the transfer is made by a rotatable selector switch member whose rotation is automatically controlled to occur in such a direction that the change from a previous to a new connection passes through a minimum number of intermediate steps. According to a more specific object, my invention aims at devising bus transfer apparatus that connect a load bus to a preferred supply source, an alternate source, an an emergency source in this order of preference and depending upon the occurrence of voltage failure of the preferred and alternate sources.

These and other objects, as well as the means provided by the invention for achieving them, will be apparent from the following description in conjunction with the drawings which, in Figs. 1 and 2, shows the circuit diagrams of two different embodiments respectively.

In Fig. 1 the load buses are denoted by L1, L2, L3, the buses of a preferred power source by P1, P2, P3, the buses of an alternate power source by A1, A2, A3 and the buses of an emergency source by E1, E2 and E3. The load buses and the power supply buses are connected to the contact terminals of a selector switch S whose movable contact member is schematically illustrated in developed form. The contact member is revolvable in both directions between three active positions denoted by P, A and E and has an off position between positions P and A and between positions A and E. Three contacts SP connect the load buses to the preferred buses P1, P2, P3 when switch S is in position P. Three contacts SA connect the load buses to the alternate buses A1, A2 and A3 when the switch S is in position A. Three contacts SE connect the load buses to emergency buses E1, E2, E3 when switch S is in position E. The contact member of switch S is also equipped with three control contacts 1, 2, and 3. The particular design of the switch S is of no concern to the present invention. The switch may be of the drum type so that the elements SP, SA, etc., represent the contact segments of the switch drum. If desired, however, the switch may be of the cam type so

2

that then the elements SP, SA, etc., represent the cam members of the switch. The switch member S has its shaft connected to a gear 4 which is equipped with a hand wheel 91 or the like member for manual actuation. The gear is also connected to the armature 5 of a reversible motor M for automatic performance. The motor has two field windings 6 and 7 for forward and reverse operation, respectively. The forward direction of switch movement is indicated by an arrow marked F, and the reverse direction is indicated by an arrow marked R. The motor M is assumed to be of the capacitor type. The appertaining capacitor is denoted by 8.

The operation of motor M is controlled by a group of interlinked control circuits which extend through a common switch 9. This switch is to be closed when automatic operation is desired. The motor control circuits are under control by a group of voltage relays PV, AV, EV and appertaining control relays PC, AC and EC.

Voltage relay PV has its coil 11 connected across the preferred busses P1 and P3 and is equipped with two main contacts 12, 13 and two interlock contacts 14 and 15. Voltage relay AV has its coil 16 connected across the alternate busses A1 and A3 under control by the first interlock contact 14 of relay PV. Relay AV has two main contacts 17, 18 and an interlock contact 19. Voltage relay EV has its coil 21 connected across the emergency busses E1 and E3 under control by the interlock contacts 15 and 18 and also under control by a timing relay T. Relay EV has two contacts 22 and 23.

The contact of timing relay T is denoted by 24 and the appertaining relay coil by 25. Relay T picks up immediately when energized, but its dropping out is delayed a relatively long period. This delay may be secured by any suitable timing means, here schematically represented by a dash pot 26.

The control relay PC is electrically associated with voltage relay PV and has a coil 27 for controlling five contacts denoted by 28, 29, 31, 32 and 33. Control relay AC is electrically associated with voltage relay AV and has a coil 34 for controlling five contacts denoted by 35 through 39. Control relay EC is electrically associated with voltage relay EV and has a coil 41 for controlling four contacts denoted by 42 through 45.

When switch 9 is open, the selector switch S can be moved to any of its positions by turning the hand wheel 91. When switch 9 is closed and switch S is in the illustrated off position, motor M is energized and drives switch S to position

P. When that position is reached and assuming that the preferred buses P1, P2, P3 are properly energized, the motor is stopped. The preferred buses are then connected by contacts SP to the load buses L1, L2, L3. This performance comes about as follows.

Coil 11 of relay PV is energized as long as proper voltage obtains across buses P1 and P3. Hence contacts 12 and 13 close for coil 27 of relay PC the circuit

P1-12-27-44-38-13-P3 (1)

Interlock contacts 32 and 33 open and prevent relays AC and EC from picking up. Contacts 28 and 29 of relay PC close, through switch 9, for armature 5 and forward field winding 6 of motor M the circuit

P1-12-28-2-6-5-82-9-29-13-P3 (2)

Motor M turns switch S in the forward direction. When switch S reaches position P, the motor circuit (2) is opened at contact 2 and the motor stops. The load buses are now connected through contacts SP to the preferred buses.

In the event of voltage failure of the preferred source, relay PV drops out and opens the coil circuit (1) of relay PC so that the motor circuit (2) is additionally interrupted at contacts 28 and 29. If the alternate buses are under proper voltage, coil 16 of relay AV becomes energized in the circuit:

A1-14-16-A3 (3)

Relay AV picks up and opens its interlock contact 19 for preventing relay EV from being energized. Relay AV also closes its contacts 17 and 18 which energize coil 34 of relay AC in the circuit:

A1-14-17-32-34-45-18-A3 (4)

Contacts 35 and 36 of relay AC now close the motor circuit:

A1-14-17-35-2-6-5-9-36-18-A3 (5)

Motor M is again started in the forward direction and turns switch S to position A. When position A is reached, the motor circuit (5) is opened at contact 2 so that the motor stops. The load buses are now connected at contacts SA to the alternate buses A1, A2, A3.

When the voltage of the alternate source also fails, relays AV and AC drop out. Hence the series-connected interlock contacts 15 and 19 of relays PV and AV are now both closed and prepare a circuit for coil 21 of relay EV. Timing relay T has its coil 25 energized through contact 31 or contact 37 as long as either relay PC or relay AC is picked up. Consequently, relay T becomes deenergized at the moment when relay AC drops out. Then the predetermined timing period of relay T starts running. At the end of the timing period the contact 24 of relay T completes for coil 21 of relay EV the circuit:

E1-15-19-24-21-E3 (6)

Assuming that the emergency source is alive, relay EV picks up and energizes coil 41 of relay EC in the circuit:

E1-15-19-22-41-39-33-23-E3 (7)

Contacts 42 and 43 close a motor circuit through the reverse field winding 7 as follows:

E1-15-19-22-42-3-7-5-9-43-23-E3 (8)

Motor M now runs in the reverse direction and

turns switch S from position A through position P to position E. When position E is reached, the motor circuit (8) is opened at contact 3 so that motor M stops. The load buses are now connected to the emergency buses.

When switch S is in position E and voltage returns to the previously dead buses of the preferred source, relay PV picks up and its contact 15 opens the coil circuit (7) of relay EV while causing relays T and PC to pick up. Relay PC then re-energizes the motor M with its forward field winding 6 in the above-mentioned circuit (2). Hence, motor M now turns switch S from position E to position P and reconnects the load buses to the preferred buses.

When switch S is in position A and power returns to the preferred buses, relay PV picks up, relays AV and AC drop out, relay PC picks up and closes for motor M a circuit through contact 1 of switch S:

P1-12-28-1-7-5-9-29-13-P3 (9)

This circuit includes the reverse field winding 7. Consequently, motor M runs in the reverse direction and turns switch S from A to P

Similarly, when switch S is in position E and power returns to the alternate buses, relays AV, AC and T pick up and relays EV and EC drop out. Relay AC then closes the motor circuit:

A1-14-17-35-2-6-5-9-36-18-A3 (10)

Motor M runs in the forward direction and turns switch S from position E through position P to position A where the motor is stopped by the interruption of circuit (10) at contact 2. It will be recognized that the switch is always turned in the proper direction to connect the load buses to the one group of supply buses that ought to be selected.

As mentioned above, the timing relay T has the effect of delaying the response of voltage relay EV so that the emergency source is connected to the load buses only after a given period of time has elapsed from the moment of voltage failure in the alternate buses. The provision of such an intermediate timing period is desired when certain switching actions are to be performed before the newly selected supply bus can be switched over to the load buses. Depending upon the requirements of each particular application, a similar time delay can be provided before switching from the preferred buses to the alternate buses. On the other hand, the illustrated timing relay T may be omitted if no delayed action is required. One purpose for which the provision of a timed delay is advantageous will be exemplified presently.

For some applications, for instance aboard ship, it is desirable that only the preferred source and the alternate source are permanently in operative condition while the emergency source consists of a power set, such as a Diesel generator, which has to be started before the load buses are switched from the alternate source to the emergency source. The timing period provided by the illustrated relay T can be utilized to secure a proper starting of the emergency set before the selector switch performs its switching operation. A circuit suitable for starting the emergency set is exemplified in Fig. 1, although it should be understood that other designs of starting circuits may be chosen. According to Fig. 1, the relays PV and AV are equipped with additional contacts 46 and 47, respectively. Each of these contacts, when closed, connects an auxiliary power source 48, such as a battery, to the pick-up coil of an

auxiliary timing relay U. The contact 49 of relay U, when closed, connects the starting device ST of the emergency power set to the source 48 under control by a switch 50. Switch 50 may be ganged up with switch 9 so as to close when the bus transfer system is set for automatic performance. The timing relay U has a comparatively short timing interval just sufficient to keep the relay contact 49 open during the interval elapsing between the opening of contact 46 and the subsequent closing of contact 47. When either the preferred source or the alternate source is connected to the load buses, the coil circuit of timing relay U is closed so that the contact 49 is opened and the starting device ST deenergized. When the relay AV drops out, preparatory to the connection of the load buses to the emergency buses, the timing relay U closes its contact 49 shortly after the opening of contact 47 but sufficiently long before timing relay T closes its contact 33. Thus an interval of time is available for the operation of the starting device ST which puts the emergency set in operation so that emergency voltage is applied to buses E1, E2 and E3 before switch S turns to position E. Even though relay T has dropped out, switch S cannot turn until voltage is available from buses E1, E2 and E3.

It will be recognized that in the embodiment of Fig. 1, the selector switch S when moving from position E to position A, or from position A to position E passes through the position P and hence temporarily connects the load buses to the preferred buses which are deenergized at that time. In cases where such a momentary connection is undesirable, the selector switch and the appertaining control system may be designed so that the switch member has its three active positions equally spaced around the drum with off positions between each neighboring active position, and the drum motor may be controlled to rotate always in such a direction that the transfer is made from any position to any other position without passing through the unwanted position. To secure such a control, the bus transfer apparatus according to the invention may be equipped with discriminating relays as exemplified by the embodiment shown in Fig. 2.

In Fig. 2, the load buses and power supply buses are denoted by the same respective reference characters as in Fig. 1. The selector contacts SP, SA and SE of switch S in Fig. 2 corresponds to the similarly designated selector contacts in Fig. 1. Relays PV, AV, EV, T, PC, AC and EC as well as motor M in Fig. 2 correspond also to the corresponding devices of Fig. 1, and the reference numerals between 1 and 45 applied to the individual elements shown in Fig. 2 designate parts corresponding to the similarly designated elements of Fig. 1. Consequently, the design and performance of the just-mentioned devices of Fig. 2 require no further description.

In contrast to Fig. 1, however, two discriminating relays PF and PR are associated with the motor circuit controlled by the relay PC. Similar discriminating relays AR and AF are associated with the motor circuit controlled by relay AC, and two discriminating relays ER and EF are associated with the motor circuit controlled by relay EC. The coils and contacts of the discriminating relays are designated by numerals between 51 and 69 and will be referred to in the following description of the operation of the system. The switch S is equipped with contacts 71 through 76 which take the place of the control contacts denoted in Fig. 1 by 1, 2 and 3.

When the preferred group of buses is under proper voltage, and the switch S in position E with switch 9 open, the coil 11 of voltage relay PV is energized. Relay contacts 12 and 13 are closed, and interlock contacts 14, 15 are open and prevent the other voltage relays from being energized. Coil 27 of relay PC is energized in the circuit:

P1-12-27-44-32-13-P3 (11)

so that contacts 28, 29 are closed while the interlock contacts 32 and 33 are open and prevent the relays AC and EC from being energized. Nothing further happens as long as switch 9 remains open.

When switch 9 is closed, it completes a circuit for coil 51 of relay PF through contact 71 of switch S:

P1-12-28-31-56-51-71-32-9-29-13-P3 (12)

Relay PF picks up and closes at contact 52 the motor circuit:

P1-12-28-31-52-6-5-82-8-29-13-P3 (13)

Motor M turns the switch S in the forward direction so that it passes from position E through "Off (2)" to position P. When position P is reached, contact 71 in switch S opens the coil circuit (12) of relay PF so that relay contact 52 opens the motor circuit (13). Hence, the motor stops when the selector switch S is in position to connect the load buses L to the group of preferred supply buses.

Assume now that, with switch 9 closed and switch S in position P, voltage failure occurs in the preferred supply line. Then the relays PV and PC drop out. Relay PV closes its first and second interlock contacts 14, 15. Contact 14 now connects coil 16 of relay AV to the alternate group of buses and picks up, assuming that these buses have proper voltage. Contacts 17 and 18 closes and energizes coil 34 of relay AC in the circuit:

A1-14-17-32-34-45-13-A3 (14)

Relay AC picks up and closes contacts 35 and 36 which apply voltage across coil 57 of relay AF through contact 73 of switch S in the circuit:

A1-14-17-35-83-63-57-73-82-9-36-12-A3 (15)

Relay AF closes at contact 58 the motor circuit through the forward field winding 6 as follows:

A1-14-17-35-83-58-6-5-82-9-36-13-A3 (16)

Motor M runs in the forward direction and turns switch S from position P through "Off (3)" to A. When position A is reached, contact 73 opens circuit (15) so that relay AF drops out and opens circuit (16) at contact 58. The load buses are now connected to the alternate group of supply buses.

In the event of voltage failure of the alternate source, relays AV and AC drop out, coil 64 of relay EF is energized through contact 75 of switch S, and contact 65 energizes the motor with field winding 6 active to run the switch S from position A through "Off (1)" to position E. The load buses are then connected to the emergency power source.

Assume that switch S is in position A connecting the load buses to the alternate group of supply buses when proper voltage re-appears across the preferred buses. Then, the relay PV picks up and opens the interlock contact 14. As a result, relays AV and AC drop out while relay PC picks up in circuit (11). Contacts 28 and 29 of

relay PC now close for coil 54 of relay PR the following circuit through contact 72 of switch S:

P1-12-28-81-54-53-72-82-9-29-13-P3 (17)

Contact 55 closes and energizes the motor with reverse field winding 7 in the circuit:

P1-12-28-81-55-7-5-82-9-29-13-P3 (18)

Consequently, motor M now turns the switch in the return direction from position A through "Off (3)" to P so that the load buses are switched from the alternate to the preferred supply buses.

In a similar manner, the switch is turned directly from position E to A if the voltage of the alternate supply buses returns while the load buses are connected to the emergency supply buses.

It will be recognized that the relays PF, PR, AF, AR, EF, ER and the associated contact devices 71 to 76 of switch S represent a directionally discriminating control system which operates to run the motor always in the direction required to pass from any one to another operating position without passing through the unwanted position.

It will be understood by those skilled in the art after studying the foregoing disclosure that apparatus according to the invention may be modified in various respects and may be equipped with individual devices and circuit elements other than those specifically described without departing from the objects and principles of the invention and within the essential features of the invention set forth in the claims annexed hereto.

I claim as my invention:

1. Bus transfer apparatus, comprising load buses, a plurality of groups of supply buses, a selector switch disposed for selectively connecting said load buses to one of said respective groups of supply buses at a time, a motor in driving connection with said switch, a plurality of voltage-responsive relay means connected to said respective groups of supply buses and sequentially interlocked with each other so that one of said relay means when active blocks action of the subsequent relay means and when inactive permits action of the next relay means, a plurality of circuits connected to said motor and controlled by said respective relay means for energizing said motor when said respective relay means is active, and a plurality of control contact means disposed in said respective circuits and associated, in displaced relation to each other, with said switch so as to deenergize said motor when said switch is in the position where said load buses are connected to that group of supply buses whose relay means is active at a time.

2. Bus transfer apparatus, comprising a plurality of groups of supply buses, load buses, a selector switch having a switch member movable through a plurality of positions and having selector contact means attached to said supply buses and load buses and disposed for connecting said load buses to a different group of supply buses in different respective positions of said switch member, a motor in driving connection with said switch member, a plurality of voltage-responsive relay means connected to said respective groups of supply buses and sequentially interlocked with each other so that one of said relay means when active blocks action of the subsequent relay means and when inactive permits action of the next relay means, a plurality of circuits controlled by said respective relay means and connected between said motor and said respective groups of supply buses for ener-

gizing said motor from one of said groups depending upon which relay is active at a time, and a plurality of control contact means disposed in said respective circuits and associated, to each other, with said switch member so as to open said respective circuits when said switch member is in the one position wherein said load buses are connected with the one group of supply buses whose relay means is active.

3. Bus transfer apparatus, comprising load buses, three groups of supply buses, a selector switch for connecting said load buses to one of said respective groups, a first voltage relay having a first coil connected to a first one of said groups and having first contact means, a first interlock contact and a second interlock contact all controlled by said first coil, a second voltage relay having a second coil connected to a second one of said groups under control by said first interlock contact to be capable of picking up only when said first relay is dropped out, said second relay having second contact means and a third interlock contact controlled by said second coil, a motor in driving connection with said switch, three circuits attached to said motor for energizing said motor, one of said circuits being controlled by said first contact means to be energized when said first relay is picked up, another one of said circuits being controlled by said second contact means to be energized when said second relay is picked up, circuit means controlled by said second and third interlock contacts and connected to said third circuit for energizing the latter when said first and second relays are both dropped out, and control contact means disposed in said respective circuits and associated, in displaced relation to each other, with said switch so as to open said respective circuits to deenergize said motor when said switch is positioned to connect said load buses to that group of supply buses whose associated one control circuit is energized.

4. In bus transfer apparatus according to claim 3, said circuit means for controlling said third motor control circuit comprising a timing device controlled by said second relay, and a third voltage relay connected to said third group of supply buses under control by said timing device and having third contact means for energizing said third circuit after the timing period of said timing device has elapsed from the drop-out moment of said second relay.

5. In bus transfer apparatus according to claim 3, said three energizing circuits being connected across said three respective groups of supply buses.

6. Bus transfer apparatus, comprising load buses, a plurality of groups of supply buses, a selector switch disposed for selectively connecting said load buses to one of said respective groups of supply buses at a time, a motor in driving connection with said switch, a plurality of voltage relays connected to said respective groups of supply buses and sequentially interlocked with each other so that one of said relays when energized prevents energization of the subsequent relays and when deenergized permits energization of the next relay, a corresponding plurality of contactors connected to said respective voltage relays to be controlled by said relays, a plurality of energizing circuits connecting said motor with said groups of supply buses respectively under control by said respective contactors, and a plurality of control contact means disposed in said respective circuits and associated, in displaced relation to each other, with said switch so as to deenergize

said motor when said switch is in the position where said load buses are connected to that group of supply buses whose voltage relay is picked up at a time.

7. In bus transfer apparatus according to claim 6, said contactors having respective coil circuits connected under control by said voltage relays to said respective groups of supply buses to be energized from said respective groups, each of said contactors having interlock contacts, and said coil circuit of each contactor extending through respective interlock contacts of the other contactors so that only one of said coil circuits can be energized at a time.

8. Bus transfer apparatus, comprising load buses, three groups of supply buses, a selector switch having a member rotatable through three positions and having contact means disposed to connect said load buses to said individual respective groups in said respective positions, three voltage relays connected to said respective groups of supply buses and sequentially interlocked with each other so that one of said relays when energized prevents energization of the subsequent relays and when deenergized permits energization of the next relay, a reversible motor having two energizing circuits for controlling said motor to run in forward and reverse direction respectively, selective control relay means having contacts connected to said voltage relays and to said switch to be controlled in dependence upon the obtaining position of said switch member and upon which voltage relay is active at the time, whereby said motor is caused to turn in the direction needed to switch said load buses from the previously connected group of supply buses to the group to be newly connected.

9. Bus transfer apparatus, comprising load buses, three groups of supply buses, a selector switch attached to said load buses and supply buses and having a switch member rotatable through three positions and three sets of contact means closed in said respective positions for elec-

trically connecting said load buses to one of said respective groups of supply buses at a time, three voltage relays connected to said respective groups of supply buses and sequentially interlocked with each other so that one of said relays when energized prevents energization of the subsequent relays and when deenergized permits energization of the next relay, a reversible motor in driving connection with said switch member and having two energizing circuits for controlling said motor to run in forward and reverse directions respectively, three pairs of control relays, the relays of each pair being mutually interlocked and having two respective control contacts connected with said two circuits respectively so that the running direction of said motor depends upon which of the two control relays is energized, each pair of control relays having two respective coil circuits for controlling said respective control contacts, said two coil circuits of each pair being controlled by a different one of said respective voltage relays so that only one of said pairs is operative at a time, and control means forming part of said switch member and being disposed in said respective coil circuits for closing and opening said coil circuits, said control means pertaining to the respective coil circuits of each pair being angularly displaced relative to each other and disposed so that in two of said three positions of said switch member either one of the coil circuits of said operative pair of control relays is closed while in the third position both coil circuits are open, said third position for the two coil circuits of each pair of control relays being coincident with the switch portion in which said load buses are connected to that group of supply buses whose voltage relay controls the same pair of control relays.
